UNITED STATES PATENT OFFICE.

GEORGE W. MACKENZIE, OF BEAVER, PENNSYLVANIA, ASSIGNOR TO CORRECT MEASURE COMPANY, OF ROCHESTER, PENNSYLVANIA, A CORPORATION OF PENNSYLVANIA.

LIQUID-MEASURING TANK.

Application filed May 24, 1926. Serial No. 111,270.

My invention relates to improvements in liquid-measuring tanks and finds application in cylindrical tanks of glass now commonly used in and constituting part of gasoline-dispensing apparatus. The problem is to place upon the tank walls legible marks of graduation which shall be at once durable and accurately placed.

The objections to forming these marks in the substance of the glass while the cylinder is being formed are (apart from the increased difficulty and cost of production) that at best such marks cannot be made easily legible, nor can they be placed with sufficient accuracy to meet the conditions. The objections to painting the marks upon the finished cylinder are that it is difficult to find a sufficiently adherent and durable paint. If applied exteriorly the paint has to endure exposure to weather and if applied interiorly it has to endure immersion in gasoline and in either case durability is a problem.

In the accompanying drawings Fig. I is a fragmentary view in elevation and Fig. II a view in horizontal section of the glass cylinder which constitutes the side wall of the measuring chamber of gasoline-dispensing apparatus of familiar form, having my invention applied to it. Figs. III and IV are views in detail, and to larger scale, showing in plan and in elevation the inter-engagement of the ends of the band in which my invention centers. Fig. V is a view in elevation and also to larger scale, showing, in comparison with Fig. I, a refinement of structure.

My invention centers in an expansible band 1 of rigid and sufficiently resilient material, upon which gasoline has no deteriorating effect, expanded within, and by virtue of expansibility adjustable in its position within, and when adjusted adapted by its expansibility to remain secured in immovable position within the glass cylinder. The band extends in horizontal plane around the vertically standing cylinder and accordingly coincides with the line at which the tide of gasoline rising or falling within the tank meets the tank wall. The material preferably employed is hard rolled brass strip.

The particular means preferably employed for effecting expansibility and con-

sequent adjustability of the band vertically 55 within the cylinder are shown in Figs. III and IV. The band is made somewhat longer than the interior circumference of the cylinder, the ends are overlapped, and the tip of the inner end is secured permanently or 60 separably to the web of the band, adjacent its opposite end. The drawings show a separable anchorage, consisting of a lug 2 stamped and turned from the web of the band, upon which the notched tip 3 of the 65 band at its opposite end bears.

The tip of the outer end of the band carries a keeper 4 which engaging the inner end of the band adjacent its tip holds the inner end at that point in close face to face engagement upon the outer end of the band, but allows the inner end to slide longitudinally within the keeper.

By these means the overlapping ends of the band, between the anchorage 2 and the keeper 4 may bow oppositely, as clearly shown in Fig. III.

The outer end of the band carries at an intermediate point between lug 2 and keeper 4 a threaded stem 5. This stem extends 80 radially inward and through a slot 6 formed in the band at a corresponding point adjacent its inner end. A nut 7 adjustable upon stem 5 completes the structure.

It will be perceived that when the strip 85 has been bent to circular shape, and its inner end thrust through keeper 4 and then interlocked with lug 2, the band may be reduced in diameter by sliding the inner end within keeper 4 and so increasing the downward 90 bowing of the inner end away from the upward bow of the outer end (Fig. III) and the band may be increased in diameter by sliding the inner end oppositely and so reducing the downward bowing of the lower 95 end. And it will further be perceived that, the band having been sufficiently reduced in diameter and the parts being then in the position shown in Fig. III, the band may be accurately placed within the cylinder and then by the turning of nut 7 be expanded 100 and so brought to and secured permanently in position upon the inner wall of the cylinder.

The band is necessarily of appreciable 105 width, and a narrower strip for sighting purposes, with unobstructed vision above and below, may be had by the expedient

shown in Fig. V. The band is widened for a relatively short interval, and within such widened portion an eye is cut with a narrow strip 8 extending across the eye.

5 The band manifestly may be marked with indicia of quantity or with other legible characters.

I claim as my invention:

- 10 1. An indicator for a cylindrical glass-walled container consisting of a band of rigid material adapted to be coiled within the cylinder with ends overlapping, and means engaging the overlapped ends tending to expand the coil and to hold the coiled band to engagement upon the cylinder wall.
- 15 2. An indicator for a cylindrical glass-walled container consisting of a band of rigid material adapted to be coiled within the cylinder with overlapping ends, means 20 for holding the ends of the band at their tips in engagement with the band at points adja-

cent the opposite ends of the band with the intervening portions spaced apart, such means allowing engaged portions of the band to slide one upon another, and means 25 for collapsing the spaced apart overlapping ends.

3. An indicator for a cylindrical glass-walled container consisting of a band of rigid material adapted to be coiled within the cylinder, said band being provided adjacent one end with a keeper, the band at its opposite end extending through said keeper and slidably engaged thereby, and at its tip secured to the web of the band adjacent the keeper-provided end, and means for reducing the divergence of the overlapped ends between the keeper and the point of securing.

In testimony whereof I have hereunto set my hand.

GEORGE W. MACKENZIE.
